POURING SPOUT FOR A PAINT CAN

Vern W. West, 1300 E. Mulberry St., Fort Collins, Colo.

Filed Oct. 4, 1962, Ser. No. 71,990

Term of patent 14 years

(Cl. D58—26)

Fig. 1

Fig. 2

Fig. 3

FIGURE 1 is an isometric view of a pouring spout for a paint can taken from the top and front showing my new design; and

FIGURE 2 is an isometric view thereof taken from the bottom and rear.

FIGURE 3 is a side elevational view thereof.

I claim:

The ornamental design for a pouring spout for a paint can, as shown.
